[57] CLAIM

The ornamental design for a vacuum cleaner nozzle, as shown.

DESCRIPTION

FIG. 1 is a front elevational view of our new vacuum cleaner nozzle showing our new design;

FIG. 2 is a rear elevational view thereof;

FIG. 3 is a top plan view thereof;

FIG. 4 is a bottom plan view thereof;

FIG. 5 is a side elevational view thereof, the opposite side is a mirror image thereof; and

FIG. 6 is a perspective view thereof.

*FIG. 1.**FIG. 2.**FIG. 3.**FIG. 4.**FIG. 5.**FIG. 6.*
